OIL BURNING APPARATUS

Reginald W. Beckett, Rocky River, Ohio, assignor to Cleveland Steel Products Corp., Cleveland, Ohio, a corporation of Ohio

Application August 11, 1936, Serial No. 95,395

7 Claims. (Cl. 158—4)

This invention relates to oil burning apparatus, more particularly to oil burning apparatus of the horizontal rotary type.

One of the objects of the present invention is to provide a means by which a rotary type oil burning apparatus may be quickly and easily mounted as a unit in a furnace structure.

Another object is to provide a furnace-burner unit of such new and improved construction that the burner, including at least a portion of its controls, may be placed in and removed from the furnace unit as a unitary structure with a minimum of time and labor.

Another object is to provide a furnace-burner unit of the wall flame type, wherein the fuel is projected above a hearth element and wherein combustion is initiated adjacent a substantially endless element located near the wall of the furnace, of such new and improved structure that the burner, hearth, and at least a portion of the associated parts may be quickly and easily mounted in and removed from the furnace unit as a unitary structure.

With the above and other objects in view, the present invention consists in certain features of construction and combinations of parts to be hereinafter described with reference to the accompanying drawings, and then claimed.

In the drawings, which illustrate a suitable embodiment of the present invention,

Fig. 1 is a front elevation of the furnace-burner unit;

Fig. 2 is a side elevation of the furnace burner unit, a portion of the same being broken away to show the oil burner unit in assembled position;

Fig. 3 is a section taken approximately on line 3—3 of Fig. 1;

Fig. 4 is a view showing the burner unit partially inserted in the furnace unit;

Fig. 5 is a perspective view of the opening closure member;

Fig. 6 is an enlarged plan view of the burner unit;

Fig. 7 is a vertical section through the burner unit shown in Fig. 6;

Fig. 8 is a front elevation of the burner unit, a portion thereof being in section;

Fig. 9 is a perspective view of one of the flame deflectors;

Fig. 10 is a section taken on line 10—10 of Fig. 6;

Fig. 11 is a plan view showing the passage of air in the structure;

Fig. 12 is a fragmentary front elevation of one of the lower corners of the furnace unit;

Fig. 13 is a section taken on line 13—13 of Fig. 12; and

Fig. 14 is a section taken on line 14—14 of Fig. 13.

Referring to the accompanying drawings, in which like numerals refer to like parts throughout the several views, there is shown, for the purpose of illustration, a furnace of the warm air type, and a rotary burner of the wall flame type, i. e., a burner in which the fuel is projected centrally from within the furnace combustion chamber and impinged against a substantially endless element, located near the furnace wall, for combustion.

Heretofore, in burners of this type, it has been necessary to assemble the burner, the hearth, the fuel intercepting member and controls, such as oil valves, transformer and ignition electrodes, as separate units. This requires considerable time and labor, due to the fact that a large portion of the assembly work has to be done within the furnace combustion chamber where the space is limited.

In accordance with the present invention, these parts are assembled together, apart from the furnace, and are mounted within the furnace as a unitary structure, and may be removed from the furnace as such.

It is to be understood, also, that the invention is applicable to furnaces other than the hot air type, and to rotary burners other than the wall flame type.

Referring to Figures 6, 7 and 8, the unitary burner structure is carried by a supporting casting 1 having a horizontal portion 2, downwardly extending side portions 3 and a downwardly extending rear portion 4, and the forward portion of which has an opening 5 defined by the top and side portions. The top or horizontal portion 2 has an opening 6 offset toward the rear portion 4, 40 but located centrally between the side portions 3.

Positioned upon the top or horizontal portion 2, substantially coaxial with the opening 6, is an annular sheet of insulation 7, and supported on the insulation 7 is a casting or plate 8 which supports the distributing device 9 and hearth structure to be hereinafter described. The plate 8 is secured to the horizontal portion 2 by means of bolts 8a extending through the insulation 7.

It will be noted that the plate 8 is provided with an opening 10, concentric, spaced inner and outer upwardly extending flanges 11 and 12, respectively, and an arcuate portion 13 of larger radius at the forward end. The portion 13 has an upwardly extending flange 14, and extending into

grally from the plate 8 in a rearward direction are spaced locating portions 15 of substantially the same radii as the arcuate portion 13, each of which has a radial flange 16 united with the outer flange 12.

Formed on the upper portion 2 are spaced upwardly extending lugs 17, which, as shown in Fig. 6, have faces 18 concentric with the flange 14, but spaced therefrom.

10 The distributing unit 9 includes an annular casing 18 extending through the opening 10, and having a circumferential flange 19 at its lower end, which flange 19 abuts the under side of plate 8 and is secured thereto by bolts 20, the heads of which seat upon portions 21 extending radially inwardly from the opening defining flange 22 of the plate 8.

Supported by brackets 22 secured to the flange 19 is a motor 23 having a hollow shaft 24, the ends of which project beyond the motor proper. The lower end of the shaft 24 carries a threaded element 25, the threads thereof running in a direction opposite to the direction of rotation of the shaft 24. The element 25 is surrounded by 25 an oil receiving casing 26 secured to the motor housing.

The upper end of shaft 24 carries a closure cap 27 having radially extending oil discharge tubes 28 for receiving oil from the hollow shaft 30 24, and a plate 29 having fan blades 30 on the underside thereof.

The annular casing 18 is preferably provided with shutter controlled air openings 31.

The oil receiving casing 26 is connected by a 35 conduit 32 with suitable oil control valves 33, which, in turn, are connected by a conduit 34 with a source of fuel supply. The control valves are supported by a bracket 35 carried by a cross member 36 which extends between the side portions 3 of the supporting casting 1.

Seating against the radially outer face of the flange 11 is an upwardly extending endless metal ring 37 of suitable heat resistant sheet metal, and similarly fitting against the radially inner face 45 of the flange 12 is an endless metal ring 38, also of heat resistant sheet metal. The rings 37 and 38 are provided with spaced L-shaped stampings 37a which seat upon the plate 8 which support the rings thereon.

50 The space between the ring 37 and the casing 18 is filled in with a suitable refractory material 39, the level of which is below the ring 37 as shown in Fig. 7, and the space between the rings 37 and 38 is filled with a suitable refractory material 40, but below the upper edges of the rings, as shown in Fig. 7.

Associated with the outer ring 38 is a removable endless oil intercepting member 41 which fits within the ring 38 and seats upon the refractory 60 40. This member carries a plurality of deflecting elements 42 of heat resistant sheet metal. Each element 42 is provided with down-turned portions 43 which are formed with slots 44 that fit about the member 41, as shown in Fig. 7, to support the element above the edge of the member 41, a solid portion 45 extending inwardly and downwardly at an angle, and narrow outer portions 46 extending alternately upwardly and downwardly at an angle. The elements 42 are arranged on the member 41 in closely spaced relation, and the solid portions 45, thereof, overhang the space 47 between the rings 37 and 38, while the alternately inclined portions 46 extend outwardly beyond the ring 38.

75 The oil discharged from the distributing unit,

as will be later more fully described, impinges against the endless member 41, and during the starting period is ignited by means of sparks produced between the member 41, which is grounded to form one electrode and electrodes 48. The electrodes 48 are substantially diametrically opposed, and each comprises a vertical rod having a lower portion 48a encased within a non-conductive casing 49, and an upper portion 48b which is reversely bent and formed with a tip 10 50 spaced from the member 41. The casing 49 is mounted in a preformed refractory element 51 which is embedded in the refractory 39 substantially at the level thereof adjacent the inner endless ring 37.

15 As shown in Fig. 8, the encased portion of each electrode extends downwardly through the refractory 39, the plate 15 and the insulation 7 into the space 52 within the supporting casting 1. The ends of the electrode portions 48a are provided with terminal connectors 53 which are connected by wires 54 with a transformer 55 supported on the cross member 36.

20 As will be seen in Figs. 6, 10 and 11, the looped portions 48b of the electrodes are arranged at 25 an angle and are directed in the direction of rotation of the distributing unit, and also, the ring 37, in advance of each electrode, is formed with a slot 56 extending to the level of the refractory materials 39 and 40 as shown in Figs. 6 and 8. 30

The leads for the motor 23 are encased within a conduit 57 and connected with the outlet box portion 55a. The leads 58 for the outlet box portion 55a are enclosed within a conduit 59.

35 Referring to Figs. 1 to 4, the furnace shown for illustration, includes an annular shell 60 having an upper end 61 and a lower end 62. The shell 60 is provided with a rectangular shaped opening 63 which is defined by an extension 64 of the lower end 62, an outwardly extending upper flange 65 and outwardly extending side flanges 66, joined with the ends of the extension 64 and the upper flange 65. The marginal edges of the flanges 65 and 66 are formed with flanges 67, and the extension 64 is inclined upwardly slightly 45 and provided with a narrow flange 64a.

40 The unitary burner structure comprising the elements previously described, with the exception of the endless member 41 and deflector elements 42, is inserted in the furnace by sliding the assembled unit through the opening 63 over the lower or bottom end 62 of the furnace in the manner shown in Fig. 4. Before the unitary structure is completely moved into position, the lower portion of the furnace is arranged with a 50 suitable insulation material 68 such as mineral wool, in such a manner that when the unitary structure is moved into its assembled position, the spaces between the rear portion 4 and side portions 3 and the casting 1 will be filled with 55 the insulation material 68.

55 When the unitary burner structure is in its final assembled position, the extending portions 15 of the plate 8 engage with the wall of the shell 60 and locate the same. Also, the outer face 65 of the flange 14 of the arcuate portion 13 substantially forms a circumferential continuation of the inner face of the shell 60.

60 After assembly of the unitary burner structure, an arcuate plate 69 is positioned within the opening 63 with its lower end seated on the portion 2 of the casting 1, and positioned between the flange 14 and the faces 18 of the lugs 11, and with the side edges 70 abutting the flanges 66 adjacent the inner edges thereof to form a cir- 75

cumferential continuation of the shell 60 and provide a continuous wall surface for some distance above the burner structure.

The joints between the edges 70 of the plate 69 and the flanges 66 are then preferably sealed with a suitable refractory.

The space between the outer ring 38 and the circumferential furnace wall is next filled with a suitable heat insulator 11, such as for example, asbestos flour, after which the endless member 41, with the deflector elements 42 assembled thereon, is then moved through the space above the plate 69 in a tilted position into the furnace chamber and disposed in position within the ring 38.

A front plate 73 is then secured to the side flanges 67 by means of screws, the plate 73 having an open frame like portion 74b fitting around the top and sides of the casting 1 as shown in Figs. 1 and 2, the open portion thereof carrying a grill 15. The space closed in by plates 73 is filled with a suitable insulation material 72, such as, for example, mineral wool. A second front plate 73b is secured to the flanges 66 above the plate 73, and carries a door frame 14 and door 74a.

Bridging the space between the plate 69 and the plate 73b is a member 76 which is supported thereby. The plate 73, plate 73b, member 76 and portion 74b completely seals in the insulation 68 and 72. The joints between the member 76 and plates 69 and 73b and between the member 76 and the side flanges 66 are preferably sealed by means of a suitable refractory cement.

Although not shown in detail, a suitable jacket 77 surrounds the furnace unit, portions of which are connected with the front plates 73 and 73b. Also that portion only of the furnace with which the present invention is associated, has been shown in detail.

The unitary burner structure may be easily and relatively quickly removed from the furnace by first removing the front plate 73, insulation 72 and plate 69, after breaking the refractory joint seals previously described, and, then, after removing the member 41 and elements 42, or elements 42, alone, by sliding the casting 1 through the opening 66.

During the initial starting period, the distributing head discharges the oil and air in a radial direction where they are intercepted by the member 41 and atomized through impact, and ignited by the sparks passing between the electrodes 48 and member 41, the resulting flame burning from the space 47 between the ring 37 and member 41.

The member 41 and deflector or flame placing elements 42, become hot due to the flame and heat of combustion, and the alternately inclined portions 46 thereof, and in fact, the elements 42 assume a red heat, with the result that the vaporized combustible mixture rises and is deflected by the portions 45 through the spaces between the member 41 and portions 42 where it burns between the member 41 and the face of shell 60 in an annular ring of flame, which has a rotary wall wiping action, the heated portions 46 serving to further vaporize the mixture and cause turbulence.

The burner structure per se and the construction of the member 41 and deflecting elements 42 associated therewith, and the electrodes and arrangement thereof with respect to the member 41 form the subjects matter of co-pending applications.

The invention shown and described is rela-

tively simple in construction and provides a means whereby a rotary burner, including its associated parts and a hearth may be conveniently and quickly inserted in and removed from a furnace as a unitary structure.

Although a single embodiment of the invention has been herein shown and described it will be understood that numerous modifications of the construction shown may be resorted to without departing from the spirit of this invention as defined in the appended claims.

What I claim is:

1. Apparatus of the character described comprising a furnace unit having a wall defining the sides of a combustion chamber, said wall having an opening therein approximating the width of said chamber, and a hearth structure movable as a unit through said opening to form the bottom of said combustion chamber, said furnace unit also having a removable wall member arranged to cooperate with the sides of said opening to form a continuation of said wall across said opening.

2. Apparatus of the character described comprising a furnace unit having a wall defining the sides of a combustion chamber, said wall having an opening therein extending from the bottom of said unit to a region intermediate the top and bottom thereof, a supporting element having a hearth structure supported thereby, said supporting element and hearth structure being movable as a unitary structure through said opening into the interior of said unit to form the bottom of said combustion chamber, and a removable wall member cooperative with said wall to form a continuation thereof across said opening above said hearth structure.

3. Apparatus of the character described comprising a furnace unit having a wall defining the sides of a combustion chamber and supporting said unit, said wall having an opening therein approximating the width of said chamber, and a hearth structure having a substantially endless upwardly extending flame wall adjacent the periphery thereof and a central opening therein, said hearth structure including said flame wall being movable as a unitary structure into the interior of said unit at a region well above the bottom of said unit to form the bottom of said combustion chamber and to provide a chamber of substantial volume between said hearth structure and the plane of the bottom of said unit.

4. Apparatus of the character described comprising a furnace unit having a wall defining the sides of a combustion chamber, said wall having an opening therein approximating the width of said chamber, and a hearth structure having a substantially endless upwardly extending flame wall adjacent the periphery thereof and a central opening therein, said hearth structure being movable as a unitary structure through said opening into the interior of said unit to form the bottom of said combustion chamber, said furnace unit including a removable wall member cooperative with said hearth structure and with said combustion chamber wall to form above said hearth structure a continuation of said combustion chamber wall across said first mentioned opening.

5. Apparatus of the character described comprising a furnace unit having a wall defining the sides of a combustion chamber, said wall having an opening therein approximating the width of said chamber, and a hearth structure including a support having a horizontal portion and downwardly extending side portions and a hearth

proper supported on said horizontal portion, said hearth structure being movable as a unit through said opening into said combustion chamber to form the bottom thereof.

6. Apparatus of the character described comprising a furnace unit having a wall defining the sides of a combustion chamber, said wall having an opening therein approximating the width of said chamber, and a hearth structure including a support having a horizontal portion and downwardly extending side portions and a hearth proper supported on said horizontal portion, said hearth structure being movable as a unit through said opening into said combustion chamber to form the bottom thereof, and means cooperable 10 with said wall and with said hearth structure to

form a continuation of said wall above said hearth structure across said opening.

7. Apparatus of the character described comprising a furnace unit having a wall defining the sides of a combustion chamber, said wall having an opening therein approximating the width of said chamber, a hearth structure including a support and a hearth body thereon, movable as a unit through said opening to form the bottom of said combustion chamber, said support having a portion extending below the upper edge of said opening, and a wall member seating on said extending portion and cooperating with the side edges of said opening to form an unbroken continuation of said wall across said opening.

REGINALD W. BECKETT.
